UNITED STATES PATENT OFFICE.

ARTHUR G. REMHILT, OF PHILADELPHIA, PENNSYLVANIA.

PHONOGRAPH ATTACHMENT.

1,304,513.

Specification of Letters Patent. Patented May 20, 1919.

Application filed February 1, 1918. Serial No. 214,957.

To all whom it may concern:

Be it known that I, ARTHUR G. REMHILT, citizen of the United States, residing at Philadelphia, in the county of Philadelphia and State of Pennsylvania, have invented 5 new and useful Improvements in Phonograph Attachments, of which the following is a specification.

This invention relates to phonograph attachments, and one object is to provide certain novel means for guiding a thread across the needle or stylus, in order to secure improved results in the reproduction of the record.

15 A further object is to provide a device adapted to be carried by the casing retaining the diaphragm, said device being detachable and serving to mount a plurality of winding elements adapted to carry a thread 20 along opposite sides of the needle and across the edge thereof.

With the foregoing and other objects in view, the invention consists in the novel construction, combination, and arrangement of 25 elements hereinafter described and claimed.

In the drawings,

Figure 1 is a view in side elevation showing means for mounting reels or spools for the thread so that the latter shall pass across 30 the needle.

Fig. 2 is a perspective view of the ring member in which the spools are mounted.

Fig. 3 is a perspective view of the device for guiding the thread across the needle.

35 Fig. 4 is a perspective view of the needle or stylus, the shank portion of which passes through the central portion of the device appearing in Fig. 3.

In carrying out my invention, I provide a 40 retaining device of resilient material including a ring member 10, having a plurality of laterally extending ears near each end thereof, the ears of one pair being designated 11 and 12 and those of the other pair being designated 13 and 14. The ears 11 and 13 may be slotted as shown at 15, and between the ears of each pair is mounted a thread winding device which may be in the form of a reel 16 rotated by a thumb member 17.

The term thread is used in the generally accepted sense, and indicates a fibrous thread.

The arm 20 controlling the diaphragm is connected with a bar 21 mounted in the usual and ordinary manner, and the socket 55 portion 22 for holding the needle may also be of usual construction. The needle or stylus is designated 23, and carries thereon a device formed of resilient material and shown as a whole at 25, this device including 60 an apertured central portion 26, the aperture accommodating the shank of the needle, and the ears 27 being bent into the position shown for retaining the elements in proper relation.

65 The device 25, constituting a thread guiding member, is provided with a plurality of prongs or leaf members 28, and 29 which in turn are provided with grooves 30 on the inner sides thereof, these grooves acting to 70 guide the thread on each side. The thread also passes through apertures 31 and thence to the spools or reels 16 on each side of the casing of the diaphragm. The thread passes around the needle as shown and is shifted 75 from time to time to a very slight extent allowing a new portion of the thread to rest on the point or extreme edge of the needle, in order to provide a new surface and prevent undue wear.

80 What I claim is:

1. In a device of the class described, the combination with a needle and mounting means therefor, of a fibrous thread, and a guiding device carried by the needle for 85 guiding the thread across the operative end thereof.

2. In a device of the class described, the combination with a needle and mounting means therefor, of a fibrous thread, means 90 for guiding the thread across the operative end of the needle, and means for shifting the position of the thread.

3. In a device of the class described, a needle and mounting means therefor, thread 95 guiding means carried by the shank of the needle and including a plurality of grooved prongs positioned on opposite sides of the

needle, and means for winding a thread carried by the guiding means.

4. In a device of the class described, the combination with the casing of the diaphragm, of a ring member surrounding said casing, reels mounted on said ring member, a needle and mounting means therefor, thread guiding means carried by the needle, and a fibrous thread passing through the

guiding means and engaged by the winding means.

5. An attachment for phonograph needle comprising a thread guiding member formed with shank engaging device and with prongs grooved on the inner surface thereof. 15

In testimony whereof I affix my signature.

ARTHUR G. REMHILT.
